UNITED STATES PATENT OFFICE.

ANDREW M. ALEXANDER, OF NORTONVILLE, KENTUCKY, ASSIGNOR OF ONE-HALF TO
EMOT P. ALEXANDER, OF DAWSON SPRINGS, KENTUCKY.

GEARING.

1,343,189.

Specification of Letters Patent. Patented June 15, 1920.

Application filed April 17, 1918. Serial No. 229,091.

To all whom it may concern:

- Be it known that I, ANDREW M. ALEXANDER, a citizen of the United States, residing at Nortonville, in the county of Hopkins and 5 State of Kentucky, have invented certain new and useful Improvements in Gearing, of which the following is a specification, reference being had to the accompanying drawings.
- 10 This invention relates to certain improvements in gearing and it is an object of the invention to provide a device of this general character having novel and improved means whereby it may be employed for a multiplicity of purposes.
- 15 It is also an object of the invention to provide a gearing which is provided with novel and improved means whereby the direction of travel of a driven element may be readily and conveniently reversed.
- 20 An additional object of the invention is to provide a machine provided with a supporting frame for ground working elements and which frame is arranged for movement in a vertical plane together with novel and improved means whereby said frame may be raised and wherein the mechanism for raising the frame is embodied in the structure for reversing the direction of travel of the 25 machine.
- 30 The invention consists in the details of construction and in the combination and arrangement of the several parts of my improved gearing whereby certain important advantages are attained and the device rendered simpler, less expensive and otherwise more convenient and advantageous for use, as will be hereinafter more fully set forth.
- 35 The novel features of my invention will 40 hereinafter be definitely claimed.
- 45 In order that my invention may be the better understood, I will now proceed to describe the same with reference to the accompanying drawings, wherein:
- 50 Figure 1 is a longitudinal vertical sectional view taken through an agricultural machine embodying a gearing constructed in accordance with an embodiment of my invention;
- 55 Fig. 2 is a horizontal sectional view taken substantially on the line 2—2 of Fig. 1;
- 60 Fig. 3 is a vertical sectional view taken substantially on the line 3—3 of Fig. 1;
- 65 Fig. 4 is a view partly in elevation and partly in section of the forward end of the 70 machine as herein disclosed;
- 75 Fig. 5 is a fragmentary view in top plan illustrating certain features of the reversing mechanism and the winding drum as herein included; and
- 80 Fig. 6 is a view partly in elevation and partly in section of the structure disclosed in Fig. 5, the section being taken substantially on the line 6—6 of Fig. 5.
- 85 As disclosed in the accompanying drawings F denotes a vertically disposed front frame preferably rectangular in form and which has the members thereof preferably formed of U-beams. Suitably secured as at 1 to one of the side or vertical members 2 of the frame F is a bearing or block 3 and slidably engaged with a second side member 2 of the frame F is a bearing or block 4 which is adapted to be moved in a manner which is to be hereinafter more particularly referred to. The blocks 3 and 4 are substantially 90 of duplicate construction and each of said blocks is provided with a vertically disposed recess 5 open at its lower end and which has slidably disposed therein the upstanding arm 6. Interposed between the inner or upper end of the arm 6 and the base of the recess 5 is an expandable member 7 of desired tension and which is herein disclosed as a conventional coil spring. The lower end of the arm 6 is provided with an outstanding 95 spindle 8 upon which is rotatively mounted a steering wheel S.
- 100 The spindles 8 are provided with the rearwardly directed spindle arms 9 which are connected by the steering rod R pivotally engaged therewith. Upon endwise movement being imparted to the rod R, the wheels S will be swung laterally to effect the desired steering operation.
- 105 The members 1 substantially midway thereof are provided with the inwardly directed guide brackets 10 through which are loosely directed the side members 11 of the U-shaped frame A. The base or intervening portion 12 of the frame A rests upon the 110 spring 14 herein disclosed of a semi-elliptical type and which is suitably anchored as at 15 to the lower strip 16 of the frame F.
- 115 The upper end portion of each of the side members 11 of the frame A is provided with the rearwardly and downwardly directed beam or member 17 which has its lower portion continued by the substantially horizontally disposed beam 18 engaged at its rear end with the axle 19.

The axle 19 intermediate the beams 18 has mounted thereon a pair of traction wheels 20 of a conventional type and which are spaced apart transversely of the machine so that 5 when desired the tongue of a mower or other agricultural machine may be suitably coupled to the axle 19.

The rear portion of each of the beams 18 is continued by an upwardly and rearwardly 10 inclined beam 21. The upper end portions of the beams 21 are connected by the transverse member 22. The beams 17 adjacent their upper or forward ends are also connected by the transversely disposed member 15 or beam 23.

24 denotes a vertically disposed arm pivotally connected substantially midway its length with the beam 23 for swinging movement in a direction transversely of the machine and the lower end portion of the arm 24 is provided with the extension or finger 25 loosely disposed through the opening 26 produced in the steering rod R midway thereof. By this means it will be at once 25 self-evident that the desired steering movement may be imparted to the wheels S upon requisite rocking of the arm 24. The upper portion of the arm 24 is provided with an arcuate rack 27 in mesh with a gear 28 carried by the shaft 29. The shaft 29 extends longitudinally of the machine and terminates adjacent the rear thereof. The shaft 29 is also supported by a bearing 30 carried by the beam 22 and by a bearing 31 carried 30 by a cross member 32 supported by the top side beams 33. The side beams 33 are supported by the upper portions of the beams 17 and 21 and interposed between the beams 18 and 33 is an intermediate beam 34 also 35 supported by the beams 17 and 21. The rear end portion of the shaft 29 is provided with a steering wheel 35 which is properly rotated by the operator when it is desired to effect a steering operation.

40 The bearing 4 is provided with an upstanding rack 36 having in mesh therewith a gear 37 carried by the shaft 38. The shaft 38 extends longitudinally of the machine and is rotatably supported thereby in any 45 desired manner and the rear portion of the shaft 38 is provided with a hand wheel 39. By rotating the shaft 38 in the desired direction, the bearing 4 may be adjusted vertically relative to the frame F so that the body 50 of the machine proper may be maintained in substantially a horizontal plane irrespective of the character of the surface over which the machine may travel and particularly when said surface is disposed upon a slope.

55 The springs 5 and 14 hereinbefore referred to serve to absorb the shocks and jars incident to the travel of the machine and the springs 5 further serve to permit the wheels S to have slight independent vertical movement to compensate for any slight irregularities or unevenness of the surface over which the machine is traveling.

Rotatably supported by the beams 18 adjacent the forward ends thereof is the transversely disposed shaft 40. Provided intermediate the beams 18 is a pair of oppositely directed cranks 41 with which are operatively engaged the driving rods 42 of the motor M. The motor M is preferably of an internal combustion type and for this reason 70 I provide the frame F with a tank T to contain a suitable supply of fluid fuel. The motor M as herein disclosed is supported by a transversely disposed beam 43 suitably secured to the lower portion of the beams 17. 75

Opposite ends of the shaft 40 extend outwardly of the beams 18 and said extended portions have suitably secured thereto the balance wheels 44. Also fixed to the shaft 40 adjacent the inner faces of the beams 18 80 are the gear wheels 45 in mesh with the larger gear wheels 46 carried by the transversely disposed countershaft 47 also rotatably supported by the beams 18 and at a point rearwardly of the shaft 40. The shaft 47 adjacent the gears 46 is provided with the smaller gears 48 meshing with the larger gears 49 fixed to the opposite end portions of the transversely disposed shaft 50 rotatably supported by the beams 34 at a point 90 rearwardly of the shaft 46.

The shaft 50 at a point substantially midway between the beams 34 has affixed thereto a materially large gear wheel 51 with which is adapted to be engaged the gear 52. The 100 gear 52 is slidably mounted upon the drill shaft 53, but keyed to rotate therewith. The shaft 53 is rotatably supported by the beams 33 and coacts in a conventional manner with the seed hoppers H. Coacting with the hub 105 54 of the gear 52 is a rock arm 55 carried by the forward end of the shaft 56 rotatably supported by the transverse member 57 resting upon the beams 33 and by the beam 22. The rear portion of the shaft 56 is provided 110 with a controlling handle or member 57^a whereby the requisite rocking movement may be imparted to the arm 55 to throw the gear 52 into or out of mesh with the gear 51. Each of the hoppers H is provided with a 115 supporting member 58 which overlies an end portion of the member 57 and is secured thereto in a conventional manner by the bolts 59. By removing one of the bolts 59 the hopper H may be readily swung inwardly when not in use. To further maintain the hoppers H in operative position I employ the brace members 60 suitably secured to the lower portions or shoes thereof and to the outstanding ears 61 carried by the 120 beams 34.

Rotatably supported by the beams 18 and at a point in advance of the shaft 50 is the shaft 62 having affixed adjacent each end thereof the gears 63 and 64. Meshing with 130

the inner gears 64 are the smaller gears 65 carried by the shaft 50. Rearwardly of the shaft 62 the beams 18 support another transversely disposed shaft 66. Slidably engaged 5 with the opposite end portions of the shaft 66 but keyed to rotate therewith are the sleeves 67. The outer end portions of the sleeves 67 are provided with the gears 68 adapted to mesh with the gears 63 and the 10 inner end portions of the sleeves 67 are provided with the smaller gears 69. The shaft 66 is also provided at each end portion with a sprocket 70 around which is directed the chain 71 also disposed around a larger 15 sprocket 72 fixed to the wheel 20.

When the gears 63 and 68 are in mesh the motor M will cause the wheels 20 to rotate in a direction to move the machine forward. The ratio of the various gears is 20 such as to materially reduce the speed of the wheels 20 relative to the shaft 40. In practice it has been found best to employ a motor causing the shaft 40 to rotate substantially 600 R. P. M. with the gears co- 25 acting therewith to reduce the speed of the wheels 20 to substantially 25 R. P. M. so that the machine will not travel faster than an ordinary walking gait.

Swingingly supported by the shaft 50 for 30 movement in a vertical plane is a frame B extending rearwardly of the axle 50 and rotatably supporting a shaft 73 having affixed thereto the gears 74 which are adapted to mesh, when the frame B is lowered, with 35 the gears 64 and 69 when the sleeves 67 have been moved inwardly to disengage the gears 68 from the gears 63. When in this last arrangement it will be perceived that the coaction between the gears 64, 74, and 69 40 will result in the reverse rotation of the shaft 66 resulting in a reverse movement of the machine. In practice it is essential that the sleeves 67 move in unison but in reverse directions longitudinally of the shaft 66 45 and as herein disclosed I employ an elongated lever 75 pivotally engaged at its forward end with a sleeve 76 loosely mounted on the shaft 62 and which is also pivotally connected as at 77 with a sleeve 67. A rock 50 lever 78 pivotally supported as at 79 intermediate its length has one end portion operatively engaged as at 80 with the second sleeve 67 while the opposite or inner end portion of the lever 78 is pivotally engaged with 55 the link 81. The link 81 is also pivotally engaged with the lever 75 at a point rearwardly of the shaft 66. The lever 75 is supported for swinging movement transversely of the machine and as is clearly indicated by Fig. 60 1 it will be perceived that upon the swinging movement of the lever 75 in one direction, the sleeves 67 will be moved in unison, but in reverse directions longitudinally of the shaft 66. The outer end portion of the 65 lever 75 is provided with a latch mechanism

82 of a conventional type and which coacts with the holding rack 83 supported in any desired manner by the body of the machine.

The rear end portions of the beams 18 are provided with the outwardly directed 70 boxes 84 and loosely disposed through each of the boxes 84 and in a direction longitudinally of the machine is a rod 85 having its rear end portion provided with a perforate head 86. Fixed to the rod 85 within 75 the box 84 is an enlargement 87. Interposed between the enlargement 87 and the rear end of the box 84 is an expansible member 88 herein disclosed as a conventional coil spring encircling the rod. The member 88 serves 80 to constantly urge the rod 85 rearwardly whereby the same is capable of limited yielding movement.

Pivotally engaged with the heads 86 are the side arms 89 of the substantially U- 85 shaped frame C. The frame C extends rearwardly of the beams 21 and has operatively engaged therewith a suitable ground working member or members M and herein disclosed as a plow of a conventional type. 90 The beams 21 are connected at a point substantially midway thereof by a rod 90 having secured thereto an end portion of a chain 91 which is disposed downwardly and around a sprocket wheel 92 suitably secured 95 at the rear portion of the frame C. The chain 91 then extends upwardly and passes over a sprocket 93 fixed to a second rod 94 supported by the beams 21 above the rod 90. The chain 91 is then extended forwardly 100 and secured to a winding drum D. Upon rotation of the drum D in one direction the frame C will be elevated and the ground working member or members rendered inoperative. As herein disclosed the frame C 105 may be maintained elevated through the medium of a dog 95 engaging a ratchet 96 carried by an end portion of the drum D and which serves to hold the drum against retrograde movement. The dog 95 may be 110 thrown into an inoperative position in any desired manner but preferably through the medium of a rod 97 or the like. The drum D is loosely mounted upon a shaft 98 rotatably supported by a pair of parallel members 99 maintained in proper position by the rods 100 carried by the beams 33. The ends of the shaft 98 are provided with the gears 101 in mesh with the gears 102 carried by the upper end portions of the downwardly and forwardly inclined shafts 103 supported by the members 99. The lower end portions of the shafts 103 are provided with the bevel gears 104 adapted to mesh with the bevel gears 105 carried by the 115 gears 74 when the frame B is in its lowered position. Mounted in a conventional manner upon the shaft 98 is a clutch member 106 coacting with an end of the drum D. The member 106 is thrown into or out of 120

125 130

- operative position in a conventional manner through the medium of the member 107. With the clutch 106 engaged with the drum D and the frame B in its lowered position it will be at once self-evident that upon initial reverse movement of the machine the frame C will be elevated. By this arrangement it will be self-evident that the initial rearward movement of the machine will cause the proper release of the ground working member M from the soil so that the raising or elevating of the frame C is assured. After the frame C has been properly elevated it is only necessary to disengage the clutch member 106 from the drum D and the frame C will be maintained elevated through the medium of the coacting dog 95 and ratchet 96 hereinbefore referred to. When it is desired to lower the frame C the same will fall by gravity upon disengaging the dog 95 from the ratchet 96.

Supported by the beams 33 and substantially directly above the shaft 50 is a transverse member 108 and supported by said member for rocking movement in a vertical plane is a bell crank lever L having a rearwardly directed arm 109 operatively connected through the medium of the link 110 with the frame B. Operatively engaged with the vertically disposed arm 111 of the bell crank lever is an operating rod 112 under control of the lever 114. By proper manipulation of the lever 114 the frame B may be raised or lowered in accordance with the requirements of practice.

E denotes the seat structure suitably supported by the body of the frame and extending rearwardly thereof and which is so positioned as to permit the occupant thereof to readily operate the various parts of the machine for controlling the same. The body of the machine is also provided with the rearwardly directed members 115 which may be grasped by the operator should he prefer to follow the machine as a pedestrian and in which event the seat structure E is thrown into an inoperative position.

It is to be understood that a suitable housing may be employed in connection with my machine as herein disclosed for inclosing the various operating parts so that said parts will be effectively protected against dust or other foreign substance which would otherwise have a tendency to interfere or hinder the operation of the machine. However as this is only incidental it is not believed that an illustration thereof is necessary.

From the foregoing description, it is thought to be obvious that a gearing constructed in accordance with my invention is particularly well adapted for use by reason of the convenience and facility with which it may be assembled and operated and it will also be obvious that my invention is sus-

ceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a driving element, a driven shaft operatively connected with the driving element, a pair of gears carried by the driven shaft, a second shaft, a pair of gears rotating with the second shaft and movable in unison longitudinally of said second shaft, one of said last named pair of gears meshing with one of the first named pair of gears when the last named pair of gears is in one position, and a gear mounted for movement toward or from the driven shaft, said last named gear in one position meshing with the second gear of both pairs of gears when the second pair of gears is in a second position.

2. In combination with a driving element, a driven shaft operatively connected with the driving element, a pair of gears carried by the driven shaft, a second shaft, a pair of gears rotating with the second shaft and movable in unison longitudinal of said second shaft, one of said last named pairs of gears meshing with one of the first named pair of gears when the last named pair of gears is in one position, a frame mounted for swinging movement toward and from the driven shaft and the second shaft, means for imparting swinging movement to said frame, and a gear rotatively supported by the frame and meshing with the second gear of both pairs of gears when the second pair of gears is in a second position.

3. In combination with a driving element, a driven shaft operatively connected with the driving element, a pair of gears carried by the driven shaft, a second shaft, a pair of gears rotating with the second shaft and movable in unison longitudinal of said second shaft, one of said last named pairs of gears meshing with one of the first named pair of gears when the last named pair of gears is in one position, and a gear mounted for movement toward or from the driven shaft, said last named gear in one position meshing with the second gear of both pairs of gears when the second pair of gears is in a second position, and a second driven shaft operatively engaged with said last named gear when in such position.

In testimony whereof I hereunto affix my signature in the presence of two witnesses.

ANDREW M. ALEXANDER.

Witnesses:

S. T. ASHMON,
JOHN R. COUSLER.
